(57) **CLAIM**

The ornamental design for a trim for microwave oven, as shown and described.

DESCRIPTION

FIG. 1 is a perspective view of trim for microwave oven showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front elevational view thereof, showing the trim used in connection with a microwave oven in a wall mounted state.

The phantom lines shown in FIG. 8 are provided for environmental purposes only and do not form part of the claimed design.
